ATTORNEY.

UNITED STATES PATENT OFFICE.

JOHN N. KAILOR, OF COLUMBUS, INDIANA, ASSIGNOR TO REEVES & CO., OF SAME PLACE.

JOURNAL-BEARING.

SPECIFICATION forming part of Letters Patent No. 496,482, dated May 2, 1893.

Application filed January 23, 1893. Serial No. 459,424. (No model.)

To all whom it may concern:

Be it known that I, JOHN N. KAILOR, a citizen of the United States, residing at Columbus, in the county of Bartholomew and State 5 of Indiana, have invented a new and useful Journal-Bearing, of which the following is a specification.

My invention relates to an improved journal-bearing, which is designed more particularly for the journals of the hulling and thrashing-cylinders of clover-hulling-machines.

The object of my improvement is, to provide means for adjusting the bearing laterally, so as to prevent end-wise motion of the shaft which carries the hulling cylinder, and at the same time provide for the automatic alignment of the journal-box.

The accompanying drawings illustrate my 20 invention.

Figure 1 represents a plan, showing the shaft in position in the bearing. Fig. 2 represents a central longitudinal section of the bearing. Fig. 3 represents a transverse section at —a— Fig. 2. Fig. 4 represents a plan of the bed-plate of the bearing in position, the journal-box having been removed. Fig. 5 represents a plan of the under side of the journal-box.

30 In the drawings, A, indicates a casting forming the bed-plate of the bearing. Said bed-plate is provided on its upper surface, with a circular recess, B, adapted to receive the flanges of the journal-box. Projecting from the opposite ends of the bed-plate is a pair of lugs, C, and D. Lug C is perforated centrally to receive a pivot-bolt, E, and lug D is provided with a slot, F, adapted to receive the clamping-bolt, G. Bed-plate A is 35 mounted in a recess, H, cut in the upper face of a supporting timber I, lug C resting upon the upper surface of the timber and being secured thereto by the pivot-bolt E so as to swing laterally thereon. The opposite end of the bed-plate terminating in lug D, rests upon a casting, J, which is secured to the timber I by means of the bolt, K, and is provided with an upwardly projecting lug, L, in which is mounted a set-screw, M; the arrangement being such that the end of the set-screw

rests against the edge of lug D. The journal-box consists of a lower part, N, and an upper part, O, adapted to receive the shaft, P, between them, and secured together by bolts, R, R. The flanges of the journal-box 55 are circular in outline and are adapted to fit easily into the circular recess B of the bed-plate. The under side of the journal-box is provided, on opposite sides of the center, with a pair of slightly raised bosses, S, S, each having a rounded surface adapted to rest upon the flat portion of the bottom of recess B, the arrangement being such, that, when the journal-box is in position on the bed-plate, it is free to turn on the bed-plate in a horizontal 60 plane and to rock thereon in a vertical plane. The under side of the box is also provided with a hollow boss, T, in which is mounted, concentric with the circular flange, a bolt, U, which projects through the under side of the 65 timber, the boss extending through a central aperture V, formed in the bed-plate.

The operation of my device is as follows:— The journal of the shaft being mounted in the journal-box, the box being free to turn 75 horizontally and to rock vertically upon the bed-plate, adjusts itself to the alignment of the shaft. The bed-plate is now adjusted, being swung upon the pivot-bolt E, by means of the set-screw M, until the end of the journal-box rests against the hub of the cylinder head, W, or other shoulder with which the shaft may be provided. The free end of the bed-plate is then secured in position by tightening the clamping-bolt G. By this construction 80 a journal-box is provided by means of which all end-wise movement of the shaft and the cylinder which it carries may be prevented, and all wear between the shoulder on the shaft and the end of the journal-box may 85 be taken up, the journal-box maintaining its alignment at all times.

I claim as my invention—

1. In a journal-bearing, the combination of the supporting timber, the bed-plate provided 95 with a central circular recess and pivoted at one end to the supporting timber so as to swing laterally thereon, the clamping-bolt passing through the free end of the bed-plate and the timber, the journal-box adapted to 100

receive a shaft and having a circular flange adapted to fit and to turn in the circular recess in the bed-plate, and the retaining bolt secured in the under side of the journal-box 5 and projecting through the timber, whereby the journal-box may be adjusted longitudinally upon the shaft and maintain its horizontal alignment therewith as set forth.

2. In a journal-bearing, the combination of 10 the supporting timber, the bed-plate provided with a central circular recess, and pivoted at one end to the supporting timber so as to swing laterally thereon, the clamping-bolt passing through the free end of the bed-plate 15 and of the timber, the journal-box adapted to receive a shaft and having a circular flange

adapted to fit and to turn in a horizontal plane in the circular recess in the bed-plate, said journal-box being provided, on its under side, with a rocking support interposed 20 between the journal-box and the bed-plate and having its axis at right angles to the journal-box, all arranged to co-operate substantially as set forth, whereby the journal-box may be adjusted longitudinally upon the 25 shaft and maintain its horizontal and vertical alignment therewith.

JOHN N. KAILOR.
